UNITED STATES PATENT OFFICE.

NAPOLEON TRUMBLE, OF WATSEKA, ILLINOIS.

TILE-MOLD.

1,182,061.

Specification of Letters Patent.

Patented May 9, 1916.

Application filed June 19, 1914. Serial No. 846,047.

To all whom it may concern:

Be it known that I, NAPOLEON TRUMBLE, a citizen of the United States, residing at Watseka, in the county of Iroquois and State of Illinois, have invented new and useful Improvements in Tile-Molds, of which the following is a specification.

The present invention relates to molding apparatus for concrete and analogous tiles, and one of the primary objects is to provide a relatively simple structure, by means of which tiles and the like can be quickly and accurately formed, and can be removed, without danger of injury and breakage.

The preferred embodiment of the invention is illustrated in the accompanying drawings, wherein:—

Figure 1 is a longitudinal sectional view through the preferred embodiment of the invention. Fig. 2 is a plan view of the same. Fig. 3 is a cross sectional view. Fig. 4 is a side elevation. Fig. 5 is an end elevation. Fig. 6 is a detail perspective view of one of the mold-side walls.

Similar reference numerals designate corresponding parts in all the figures of the drawings.

In the embodiment illustrated, a supporting frame is employed. This frame includes side bars 7 connected by cross bars 8 and supported on legs or standards 9, which are suitably braced, as shown at 10. The side bars 7 between the cross bars 8 have their outer sides upwardly and inwardly beveled, as illustrated at 11, so that the material which falls thereon will drop therefrom and not accumulate.

Arranged within the box formed by the side bars 7 and cross bars 8, is a mold, and this mold consists of side walls 12 that rest against the inner faces of the side bars 7 and have terminal extensions 13 which rest upon the cross bars 8 and thus support said side walls. End walls 14 are located between the side walls and serve to hold them in properly spaced relation. These end walls are located against the inner faces of the cross bars 8 and are secured thereto by screws 15 or other suitable fasteners. The side walls 12 have ears 16 cut therefrom, and turned inwardly and through these ears are adjustably threaded screws 17, which constitute supports for the pallet, one of which is shown in place and indicated at 18. Said pallet fits between the end and side walls and is of any desired form.

For the purpose of shaping and finishing the upper surface of the tile, a finishing bar 19 is slidably mounted on the structure and is capable of being reciprocated back and forth over the mold, its under face being shaped to the desired form of the tile. This shaping bar has terminal handles 20, by means of which it is manually moved and is furthermore provided with depending guides 21 extending down sufficiently far to engage the outer lower portion of the side bars 11. In order to prevent the wabbling of this finishing bar, it has connected to its center a rearwardly extending guide bar 22 which operates between a pair of upstanding guide fingers 23 carried by a cross piece 24 on the frame. This guiding means, however, permits one end of the finishing bar to be raised and lowered with respect to the other, but holds the bar at right angles to its line of movement.

For the purpose of removing the pallets with the finished tiles thereon from the mold, a hand lever 25 is employed, comprising a bar that is doubled to form spaced side arms, each side arm being fulcrumed at its rear end, as shown at 26 to one of the side bars 7. The connection between the side bars 7 constitutes a handle 28. The side arms are connected between their ends by upstanding U-shaped yokes 29 that are arranged to pass through the open bottom of the mold and engage the pallet so that the same will be lifted out of the mold when the lever is elevated.

From the foregoing, it is thought that the construction, operation and many advantages of the herein described invention will be apparent to those skilled in the art, and it will be understood that various changes in the size, shape, proportion and minor details of construction may be resorted to without departing from the spirit or sacrificing any of the advantages of the invention. For example, the molds and finishing device may have different conformations to make different types of tile, as for instance, the body tile for the roof, ridge roll, and the like.

Having thus fully described my invention, what I claim as new, and desire to secure by Letters Patent, is:—

1. In a machine of the character set forth, a supporting frame comprising angularly disposed bars, a mold therein comprising side walls located alongside certain of the frame bars and having terminal extensions

resting on the other frame bars, and transverse walls located between the side walls.

2. In a machine of the character set forth, a supporting frame, comprising angularly disposed bars, a mold therein comprising side walls located alongside certain of the frame bars and having reduced terminal extensions resting on the other frame bars, transverse walls located against said frame bars and between the side walls, and fastening devices securing the transverse walls to the bars alongside which they are located.
3. In a machine of the character set forth, a frame, a mold located therein and comprising angularly disposed walls, certain of said walls having inset integral ears, and pallet supporting devices adjustably mounted in said ears.
4. In a machine of the character set forth, a frame, a mold located therein and comprising angularly disposed walls, and pallet-supporting means in said mold, including ears integral with and inset from the mold walls.
5. In a machine of the character set forth, a supporting frame including side and cross

bars, a mold located within the frame and comprising side walls located alongside the side bars and having a terminal extension resting upon the cross bars, end walls located against the cross bars and between the side walls, means for fastening the end walls in place, said side walls having inset integral ears, and pallet supporting screws adjustably threaded through the ears.

6. In a machine of the character set forth, a supporting frame, a mold therein having an open bottom and pallet-lifting means comprising a hand lever pivoted at its rear end to the frame and having a hand grip at its front end, and spaced upstanding pallet-engaging yokes having downturned ends connected to the lever, the intermediate portions of said yokes moving in a path to raise and elevate the pallet placed in the mold.

In testimony whereof I have hereunto set my hand in presence of two subscribing witnesses.

NAPOLEON TRUMBLE.
